UNITED STATES PATENT OFFICE.

HERMAN E. SCHULSE, OF NEW YORK, N. Y., ASSIGNOR TO H. E. SCHULSE, INC., A CORPORATION OF NEW YORK.

DESIGN FOR A SHOE-SHINING SEAT.

Application filed June 5, 1928. Serial No. 26,993. Term of patent 14 years.

To all whom it may concern:

Be it known that I, HERMAN E. SCHULSE, a citizen of the United States, and residing at New York city, in the county of New York and State of New York, have invented a new, original, and ornamental Design for Shoe-Shining Seat, of which the following is a specification, reference being had to the ac-

companying drawings, forming part hereof.

The figure is a perspective view of the shoe shining seat showing my new design.

I claim:

The ornamental design for a shoe shining seat as shown.

HERMAN E. SCHULSE.
